WARREN S. BELLOWS, OF EAST ORANGE, NEW JERSEY

TABLE TOP

Application filed October 1, 1926. Serial No. 138,823.

This invention relates to an improvement in table tops, more particularly for tops of light-weight or folding tables.

It is an object of the invention to provide a means for securing the cloth cover over the top of a folding table without the necessity for a separate rim or molding around the outer edge of the table top.

Another object of the invention is to provide a cheap and convenient means for securing the top in the top frame of a table of this type, having all the advantages of the prior construction and being easier to apply.

Another object of the invention is to provide a fabric covered table top in which the fabric is protected by a transparent flexible covering permanently secured to the table.

Various other objects and advantages will appear as my description proceeds.

In the drawings:

Figure 1 is a plan view of a portion of the table top showing my invention applied thereto;

Figure 2 is a sectional view through a portion of the top and top frame, illustrating how the connection is made between these members; and

Figure 3 is a perspective view similar to Figure 2, illustrating the use of the flexible covering over the fabric.

In the ordinary folding or card table, a top rim is provided into which is fitted a table top, made usually of light wood, plaster board or cardboard. The legs are secured to the top frame and a fabric covering is placed over the entire top and frame and secured around the edges of the top frame by means of a molding or rim. Both the top frame and the molding must be nailed and accurately fitted at the corners and metal corners attached to the rim to provide the required strength.

My present invention dispenses with the use of this outside molding or rim, the metal corners, etc., and with the securing of the flexible covering around the top frame, and simplifies the securing of the top in the frame.

In the embodiment of my invention illus-

trated, in Figure 1 the top frame is indicated by the reference numeral 1 and is provided with a rabbet or recess 2 in its inner top edge into which the edge 3 of the top 4 of the table may be received. The top 4 is preferably of some light-weight material of suitable strength, such as plaster board, cardboard, light-weight wood or the like. Secured to the top, at spaced relation, are a plurality of metal straps or staples 6, which are passed through spaced holes 7 in the top member and have one of the legs 6b of the staple bent to lie parallel with the lower plane of the top. The downward projection 8 formed by the other leg of the strap or staple 6 is provided with a perforation for receiving the nail 9 by which the top is nailed to the top frame member. Any suitable number of these strap members may be used for securing the top in the top frame. Preferably three or four of the straps 6 are used on each side of the top. Inasmuch as the top member 4 is of plaster board, cardboard or other light-weight material, it is not feasible to nail or otherwise attempt to secure the strap 6 to the underside of these members, but by passing the bent straps or staples through the two holes 7 and bending one projection 6b so as to lie along the lower surface of the top member, so a securing means is provided which firmly holds the top without putting a great strain on the light-weight material of which the top is constructed. The portion 6a on the upper face of the top and the portion 6b on the bottom surface of the top being of fairly wide material, give a very firm securing means on the top without any concentrated strains.

A flexible cloth or other suitable fabric 10 is preferably stretched over the top 4 of the table and secured in the rabbet 2 between the edge of the top member and of the top frame. The fabric 10 may be clamped between these members by the pressure of these members when secured together or may be secured to the edges of the top by gluing or the like. By securing the fabric in this way, a much more simple assembly is provided than where the fabric 100

is stretched over the outer edges of the top frame and a separate molding applied, approximately three inches of fabric are saved on each edge, the outer rim or molding for 5 the top frame is eliminated and the work of assembly is simplified. The corners and the frame may be rounded and the usual metal corners omitted. The straps 6 provide a ready and easy means for securing 10 the top in the frame in a manner which permits the top and fabric covering to be removed or reapplied when desired without destroying or tearing any portion of the top or frame. The top may be nailed in 15 place at a much smaller cost than gluing the same in place and is held more secure.

In Figure 3 of the drawings a similar form of construction is used, in which the top 4 is secured in the rabbet 2 of the frame 20 1 by means of straps 6 and a cloth cover 10 is provided with a suitable transparent flexible covering 11 of transparent paper, celluloid or the like. The covering 11 is secured to the top in the same manner as 25 the flexible covering 10 and serves to protect the cover 10, while at the same time exposing the design of the cover 10 to observation. The flexible covering 11 is preferably of material which will permit washing, so that the cloth covering 10 is kept 30 bright and clean at all times and the flexible covering 11 may be cleaned by washing when desired.

It will be understood that various modifications may be made within the spirit of 35 my invention without departing from the scope of the appended claims.

What I claim as my invention is:

1. A table top construction, a top frame 40 having a rabbeted inner edge, a top member of light-weight material adapted to fit into said frame, a plurality of metal straps, each strap extending along the upper and lower surfaces of said top member and extending through two holes therein and providing a projection having a perforation 45 therein for securing the top member in the frame and means for securing the said projections to the frame.

2. A covered table top construction comprising a frame having a rabbeted inner edge, a top of relatively light weight within said frame, a plurality of metal straps, each extending along the upper and lower 55 surfaces of said top and through two holes therein, and providing a projection having a perforation therein for securing the top member in the frame, means for securing said projections to said frame, and a cover 60 for the top with a portion of the cover extending between the top and the rabbeted inner edge, the cover concealing the straps on the upper surface of the top, and filling the space between the top and the inner edge 65 of the frame.

3. A table top construction comprising a frame, a top of relatively light weight within said frame, and a plurality of metal straps for securing the top to the frame, each strap being secured to the frame below 70 the top and extending above the top and along the upper surface thereof, and being passed through an opening in the top and extending from said opening along the lower surface of the top.

4. A covered table top construction comprising a frame, a top of relatively light weight within and spaced from said frame, a plurality of metal straps each secured to the inside of the frame below the top and extending above the top and along the upper surface thereof and being passed through an opening in the top and extending from said opening along the lower surface of the top, and a cover for the top with the edges of the cover secured between the top and the frame, the cover concealing the straps on the upper surface of the top and adapted to fill the space between the top and said frame.

In testimony whereof I have affixed my signature to this specification.

WARREN S. BELLOWES.
